(57) CLAIM

The ornamental design for a grilling kilt as shown and described.

DESCRIPTION

FIG. 1 is a top, front, right side perspective view of a grilling kilt showing my new design;

FIG. 2 is a front elevational view of the grilling kilt;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a front elevational view of a second embodiment of a grilling kilt with a bib.

The dashed lines in the views illustrate stitching that forms a part of the claimed design.

The partial person shown in broken lines in FIG. 1 is included for the purpose of illustrating environment and forms no part of the claim.

1 Claim, 6 Drawing Sheets
